(57) **CLAIM**

The ornamental design for a light controller with lens, as shown and described.

DESCRIPTION

FIG. 1 is a perspective view of the top, right, and front views of a first embodiment of our design;

FIG. 2 is a perspective view of the bottom, left, and rear views of the first embodiment of our design;

FIG. 3 is a view of the right side of the first embodiment of our design, the left side view being identical in all claimed respects;

FIG. 4 is a perspective view of the top, right, and front views of a second embodiment of our design;

FIG. 5 is a perspective view of the bottom, left, and rear views of the second embodiment of our design; and,

FIG. 6 is a view of the right side of the second embodiment of our design, the left side view being identical in all claimed respects.

The only difference between the first embodiment of our design shown in FIGS. 1-3 and the second embodiment of our design shown in FIGS. 4-6 is the addition of a door in the second embodiment. Such a door is shown in dotted lines in the first embodiment and, thus, forms no part of the claimed design of the first embodiment. Moreover, the dotted lines shown in the figures represent environmental structure and form no part of the claimed design.
